(57) **CLAIM**

The ornamental design for a training apparatus as shown and described.

DESCRIPTION

FIG. 1 is a front, top, left side perspective view of a training apparatus showing my new design;

FIG. 2 is a rear, top, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view taken along line 9-9 in FIG. 3 thereof.

The broken lines in the drawings are for the purpose of illustrating portions of the training apparatus that form no part of the claimed design.
